US0D1025797S

(12) United States Design Patent (10) Patent No.: US D1,025,797 S
(45) Date of Patent: * May 7, 2024

(54) WATCH

- (71) Applicant: ROLEX WATCH U.S.A., Inc., New York, NY (US)
(72) Inventor: Maria Calvani, Cologny (CH)
(73) Assignee: ROLEX WATCH U.S.A., Inc., New York, NY (US)

() Term: 15 Years

(21) Appl. No.: 29/841,970

(22) Filed: Jun. 9, 2022

Related U.S. Application Data

- (62) Division of application No. 29/701,753, filed on Aug. 14, 2019, now Pat. No. Des. 958,682.
